UNITED STATES PATENT OFFICE.

PAUL A. GOLLNICK, JOHN J. TOOLAN, AND GEORGE HARRED, OF CHICAGO, ILLINOIS,
ASSIGNORS TO SPIEGEL, MAY, STERN COMPANY, OF CHICAGO, ILLINOIS, A COR-
PORATION OF ILLINOIS.

PRINTING MECHANISM FOR ADDRESSING MACHINES.

Application filed May 9, 1927. Serial No. 189,876.

This invention relates to printing apparatuses and particularly to printing mechanisms adapted for use in connection with addressing machines and similar devices.

The main objects of this invention are to provide an improved form of platen for applying ink to the stencil or other printing form; to provide an improved form of carriage for supporting said platen; to provide an improved form of ink transferring mechanism for transferring ink from a fountain to the platen; to provide an ink transferring mechanism having an improved form and arrangement of distributing rollers; to provide improved means for supporting said rollers to permit certain coacting rollers to be disengaged when not in use so as to avoid flattening of the composition shells; to provide improved means for operating the transferring mechanism; to provide improved mechanism for oscillating the platen carriage to move the platen toward and away from the stencil or other form; and to provide improved mechanism for intermittently rotating said platen to permit it to wipe ink from the transferring mechanism.

An illustrative embodiment of this invention is shown in the accompanying drawings, wherein:

Fig. 1 is a fragmentary plan of an addressing machine to which an improved printing mechanism has been applied.

Fig. 2 is a transverse vertical section, taken on the line 2—2 of Fig. 1, and showing the parts of the printing mechanism in the positions which they occupy at the time of making the impression.

Fig. 3 is a similar view, showing the platen in its raised position.

Fig. 4 is a vertical section taken on the line 4—4 of Fig. 1, and showing the printing mechanism in front elevation.

Fig. 5 is a transverse vertical section taken on the line 5—5 of Fig. 1.

Fig. 6 is a transverse vertical section taken on the line 6—6 of Fig. 1 and showing the train of gears.

Fig. 7 is a rear elevation of the mechanism.

An improved printing mechanism embodying this invention is adapted for use in many different types of machines but, in the specific form herein illustrated, the invention is applied to an addressing machine.

Inasmuch as this invention relates particularly to the printing mechanism, parts of the machine not relating thereto and believed to be unnecessary to a complete understanding of the invention have been omitted from the drawings.

In the specific form herein shown, the improved printing mechanism comprises an intermittently rotatable platen supported on an oscillating carriage which is actuated by improved mechanism to move the platen into and out of engagement with the stencil. An improved ink transferring mechanism comprising a plurality of rollers is arranged to transfer ink from a fountain to the platen which wipes the ink from one of the distributing rollers. Certain of the rollers are made of metal and others are provided with composition shells. In order to prevent the composition rollers from becoming flattened through contact with other rollers during a long period when not in motion, improved mechanism is provided for moving the composition rollers out of contact with the other rollers. This last mentioned mechanism is controlled by the same means which controls the starting and stopping of the machine, so that the rollers are automatically thrown out of coacting relation with one another upon the stopping of the machine.

In the embodiment shown, the improved printing mechanism is applied to an addressing machine comprising a frame 1 having a horizontal table or bed 2, on which is mounted a pair of spaced rails 3 forming a guideway for supporting and guiding a plurality of stencils 4, which are fed seriatim through the machine by an endless conveyer 5, so as to be operated upon by the improved printing mechanism and by various other mechanisms, not shown. Extending transversely through the bed 2, is a passage 6 located below the stencil guideway for receiving a stack of envelopes, not shown, upon which the addresses are printed from the stencils.

Located directly below the stencil guideway, in vertical alinement with the platen, is a vertically movable anvil 7, which is adapted to raise the envelopes into position to be acted upon by the stencils.

In the form shown, the improved printing device comprises an impression mechanism A and an ink transferring mechanism B.

The improved impression mechanism A comprises an impression element or platen 8, rotatably mounted on an oscillating carriage 9, which is actuated so as to move the platen toward and away from the stencils 4.

In the construction illustrated, the platen 8 comprises a suitable pad 10, mounted on a metal base 11, having arms 12, which are fixed on a rotatable shaft 13 journaled in the frame 9. The face of the pad 10 is of a size and shape which will conveniently fit within the stencil in making the impression.

Fixed on one end of the shaft 13, is a mutilated gear 14 meshing with another mutilated gear 15 which is fixed on a stud 16 journaled in the oscillating frame 9 and driven through a train of gears 17, 18, 19 and 20. The gear 17 is fixed on the stud 16 and the gear 18 is loose on a shaft 21 journaled in a pair of spaced upstanding brackets 22 and 23 on the frame 1. The gear 19 is keyed to a shaft 24 journaled in the bracket 22 and the gear 20 is fixed on a drive shaft 25 which is journaled in the brackets 22 and 23. During the operation of the printing mechanism, the drive shaft 25 is rotated continuously by an electric motor or other suitable power means, not shown, which may be controlled by a foot pedal convenient to the operator of the machine.

Through the operation of the drive shaft 25, the gears 20, 19, 18, 17 and 15 are rotated continuously. During the impression operation, when the platen pad 10 is in contact with the stencil, the platen should momentarily cease rotating. For this reason, the gears 14 and 15 are mutilated so as to provide smooth portions 26 and 27 respectively 40 which slidably engage each other during the printing operation. Projecting radially outwardly from one side of the gear 14, is a cam 28, located so as to engage a pin 29 on the rotating gear 15 to insure proper meshing of the gears 14 and 15 after the printing operation.

In the specific form shown, the carriage 9, which carries the platen, comprises a pair of end members 30 connected together by integral cross braces 31 and 32. Formed on the end members 30, are bosses 33, which are journaled on bushings 33.1 on the shaft 21 which forms the pivot on which the carriage 9 oscillates.

The carriage 9 is oscillated by a mechanism which includes a pair of links 34 and 35 and a bell crank 36. The link 34 is rigidly secured to the brace 31 of the carriage, and the link 35 is pivotally connected to the inner ends of the link 34 and bell crank 36. The bell crank 36 is pivoted on a pintle 37 supported in the brackets 22 and 23 at the rear of the frame. The lower end of the bell crank 36 has a roller 38 which rides on a cam 39 fixed on the drive shaft

25, whereby the rotation of the shaft 25 imparts an oscillating movement to the carriage 9. The roller 38 is normally urged into engagement with the cam 39 by a spring 40 bearing between the lower end of the bell crank 36 and a bar 41 extending between the brackets 22 and 23.

The improved ink transferring mechanism B, as herein shown, comprises a plurality of coating rollers 42, 43, 44, 45 and 46, arranged to transfer ink from a fountain 47 to the platen pad 10. The rollers 42 and 44 are preferably made of a suitable resilient composition and the rollers 43, 45 and 46 are preferably metal.

The roller 42 is rotatable on a shaft 48 carried at its ends by a pair of arms 49, pivotally connected to the carriage members 30 by pins 50. In order to permit the roller 42 to yield when in contact with the platen 8, it is resiliently urged toward the platen by a pair of springs 51 bearing against the ends of the shaft 48 and seated in slots 52 formed in the arms 49. The roller 42 is normally urged into engagement with the roller 43 by springs 53 extending between the arms 49 and the bosses 33.

The roller 43 is fixed on the drive shaft 21. Secured to one end of the roller 43, is a gear 54 adapted to mesh with gears 55 and 56 mounted at one end of the rollers 42 and 44 respectively, for rotating the rollers 42 and 44.

The roller 44 is provided with a pintle 57 journaled in links 58, which are pivoted to a pair of levers 59 and 60 by pins 61. Extending between the links 58 and one end of the levers 59 and 60, are springs 62, which normally urge the roller 44 into engagement with the roller 43.

The levers 59 and 60 are pivoted on a shaft 63 supported in the brackets 22 and 23. Extending between the levers 59 and 60, and rigidly connected thereto, is a brace 64. Mounted on the outer end of the lever 59, is a roller 65 which engages a cam 66 fixed on the drive shaft 25, whereby the rotation of the shaft 25 oscillates the levers 59 and 60, thereby periodically moving the roller 44 out of engagement with the roller 45. The roller 44 is normally urged into engagement with the rollers 43 and 45 by means of a spring 67 extending between the arm 60 and the shaft of the roller 45.

During the operation of the printing mechanism, the roller 44 rides up and down on the roller 43 so as to move toward and away from the roller 45, to periodically wipe ink from the roller 45 and transfer it to the roller 43. When the machine is stopped, the rollers 42 and 44 are both disengaged from the other rollers. The means for disengaging the rollers 42 and 44 from the other rollers comprises an arm 68 pivoted on a stud 69 mounted in the bracket 23. Mounted on

the arm 68, is a cam 70, which engages a pin 71 on the adjacent link 58 for raising the roller 44 and its supporting links and levers, when the arm 68 is moved rearwardly. 8
8. Mounted on the arms 59 and 60, are shoulders 72 arranged in position to engage the arms 49 for lifting the roller 42 when the levers 59 and 60 are shifted under the action of the arm 68.
10 The roller 45 has a pintle 74 supported in the brackets 22 and 23. Fixed on one end of the roller 45, is a gear 45.1 meshing with a gear 46.1 fixed on the roller 46. Fixed on the other end of the roller 45 is a ratchet 75, which engages a pawl 76 pivoted on the pintle 74. Pivotally connected to the pawl 76, is a link 77 connected to the lower end of a bell crank 78, which is pivoted on a stud 79 supported on the bracket 22. Supported 20 on the upper end of the bell crank 78, is a roller 80, which engages a cam 81 fixed on the shaft 25, whereby the rotation of the shaft 25 oscillates the bell crank 78 thereby rotating the rollers 45 and 46 in a step-by-step movement. The rollers 44 and 45 rotate in the same direction, and, therefore, when the two are in contact, the roller 44 wipes ink from the surface of the roller 45. In order to permit variation of the throw of the pawl 30 76, a pin and slot connection 82 is provided between the link 77 and bell crank 78. The pawl 76 is normally retracted by a spring 83 which extends between the link 77 and a peg 84 mounted on the base bed 2. The spring 83 also serves to retain the roller 80 in contact with the cam 81.

40 The inking roller 46 is supported in a pair of hangers 85 pivoted at one end on a pin 86 extending across the fountain 47. The roller 46 is yieldingly urged into contact with the roller 45 by springs 87 bearing between the outer ends of the hangers 85 and the bottom of the fountain 47.

45 Mounted on the frame 1 at the rear of the printing mechanism, is an electric switch 88 having an operating arm 89 connected to the arm 68 by a link 90. The switch 88 is in the electric circuit which controls the operation of the printing mechanism and is 50 opened and closed by the movement of the arm 68, which simultaneously moves the rollers 42 and 44.

55 In operation, the stencils 4 are fed in a step-by-step movement along the guideway 3 so as to position one stencil at a time directly below the platen 8.

60 During the operation of the printing mechanism, the shafts 21 and 25 rotate continuously for driving respectively the ink distributing rollers and the cams 39, 66 and 81. Through the operation of the cam 39, the carriage 9 is oscillated so as to move the platen pad 10 into and out of engagement with the stencils. Through the action of the 65 gears 14, 15, 17, 18, 19 and 20, the platen 8

rotates continuously except during the brief period when the impression is made.

Through the action of the cam 81, the pawl 76 moves the roller 45 step-by-step to wipe ink from inking roller 46. Through the action of the cam 66 and spring 67, the roller 44 is moved into and out of engagement with the roller 45 for transferring ink from the roller 45 to the roller 43. The roller 43 transfers the ink to the roller 42 from which the ink is transferred to the platen pad 10.

When the machine is to be stopped, the arm 68 is shifted rearwardly. This movement of the arm 68 opens the switch 88 and lifts the rollers 42 and 44 out of contact with the rollers 43 and 45, through the action of the cams 72 and 70. Forward movement of the arm 68 lowers the rollers 42 and 44 and closes the switch 88.

Although but one specific embodiment of this invention has been herein shown and described, it will be understood that numerous details of the construction shown may be altered or omitted without departing from the spirit of this invention as defined by the following claims.

We claim:

1. A device of the class described comprising a bed, a reciprocating frame, a platen journaled in said frame, mechanism for rotating said platen and simultaneously reciprocating said frame, and means on said reciprocating frame for transferring ink to said platen during its rotation.

2. A device of the class described comprising a bed, a reciprocating frame, a platen journaled in said frame, mechanism for intermittently rotating said platen, means for transferring ink to said platen, and mechanism for moving said platen toward said bed during the intermission in its rotation.

3. A device of the class described comprising a platen, an ink distributing roller, an ink transferring roller normally engaging said distributing roller and arranged to transfer ink to said platen, resilient means normally urging said transferring roller toward said platen, and means for manually moving said transferring roller out of engagement with said distributing roller.

4. A device of the class described comprising a reciprocating frame, a rotatable platen on said frame, an ink distributing roller, an ink transferring roller on said frame adapted to transfer ink to said platen, resilient means normally urging said transferring roller toward said platen, other resilient means normally urging said transferring roller into contact with said distributing roller, and means for manually moving said transferring roller out of contact with said distributing roller.

5. A device of the class described com-

prising a pair of distributing rollers arranged on substantially parallel fixed axes, a transferring roller adapted to simultaneously engage both of said distributing rollers, means normally urging said transferring roller into contact with one of said distributing rollers, mechanism for intermittently moving said transferring roller out of contact with the other distributing roller, and means for manually moving said transferring roller out of contact with both of said distributing rollers.

6. A device of the class described comprising a platen, a pair of distributing rollers arranged on substantially parallel axes, a transferring roller adapted to engage one of said distributing rollers and to transfer ink to said platen, another transferring roller normally engaging both of said distributing rollers, means for intermittently moving said other transferring roller out of engagement with the other of said distributing rollers, and mechanism for manually moving both of said transferring rollers away from said distributing rollers.

7. A device of the class described com-

prising a pair of distributing rollers arranged on substantially parallel axes, a transferring roller adapted to engage both of said distributing rollers, said transferring roller being geared to one of said distributing rollers, and mechanism for intermittently rotating the other distributing roller in the same direction as the rotation of said transferring roller.

8. A device of the class described comprising a pair of distributing rollers arranged on substantially parallel axes, a transferring roller adapted to engage both of said distributing rollers, said transferring roller being geared to one of said distributing rollers, means for intermittently moving said transferring roller out of contact with the other distributing roller, and mechanism for rotating said other distributing roller in the same direction as the rotation of said transferring roller.

Signed at Chicago this 28th day of April, 1927.

PAUL A. GOLLNICK.
